UNITED STATES PATENT OFFICE

2,524,888

MATERIAL UNLOADING APPARATUS

Walter D. Fish, Claremont, N. H., assignor to
 Joy Manufacturing Company, a corporation of
 Pennsylvania

Application November 7, 1945, Serial No. 627,202

14 Claims. (Cl. 214—53)

1

This invention relates to material unloading apparatus and more particularly to a rotary dump for mine cars having associated therewith improved means for imparting hammer blows to the bottom of an inverted mine car on the dump to discharge any wet and sticky material which might be packed in the car bottom.

In the transportation of material such as coal in mines, the material is usually transported from the mine by a train of mine cars hauled by a mine locomotive, and when the train of cars reaches the mine tipple, the material is oftentimes dumped from the cars by a rotary dump which inverts each loaded car so that the material is discharged therefrom by gravity. When a mine car is inverted to discharge its contents, some difficulty has been encountered in completely discharging the packed material in the bottom of the car, particularly when the material is wet and sticky. In order to discharge the packed, wet and sticky material from the car bottom, it has been found necessary to hammer on the car bottom when the car is inverted and, as disclosed in a copending application to John C. Curtis and Elmer G. Gartin, Serial No. 627,203, filed November 7, 1945, owned by applicants' assignee, hammering on the car bottom was effected by means of pneumatic tools mounted on the rotary dump and fluid supply to the hammering tools was effected under manual control.

The present invention is an improvement over previous known means for hammering on the bottom of an inverted mine car on a rotary dump, in that the hammering means is automatically rendered effective to hammer on the car bottom when the rotary dump is rotated to invert the mine car and the hammering means is automatically rendered inactive when the dump is rotated toward its position wherein the car is right side up. In a preferred embodiment, the hammering tools are pressure fluid actuated and pressure fluid is automatically supplied to the tools when the dump is rotated to invert the mine car, and fluid supply to the tools is automatically discontinued upon initiation of dump rotation toward its position wherein the car is right side up. In the preferred embodiment, the tools are supplied with pressure fluid through a releasable coupling for connecting the fluid supply connection on the rotary dump to a source of fluid supply extraneous to the dump, and the coupling is fluid actuated so that it is automatically connected when the rotary dump assumes its position wherein the mine car is inverted and is automatically released upon initiation of rotation of

the dump toward its position wherein the car is turned right side up. In a specific embodiment, the fluid supply to the hammering tools is controlled by an automatic valve which is controlled by control means operated by an operating element on the rotary dump, and pressure fluid is conducted to the tools from an extraneous source through a releasable automatic fluid supply coupling which is automatically connected when the dump is rotated into its position to invert the mine car and which is automatically disconnected upon initiation of rotation of the dump toward its position wherein the car is turned right side up. Accordingly, the fluid supply to the hammering tools is controlled automatically by means controlled by the rotary dump so that when the dump assumes predetermined positions, the fluid supply is automatically effected or interrupted.

10 It is accordingly an object of the present invention to provide a rotary car dump having associated therewith improved means for hammering on the bottom of an inverted mine car on the dump to release the wet and sticky material which might be solidly packed in the bottom of the car. Another object is to provide a rotary dump having improved power operated hammering mechanism which is mounted on the rotary dump to rotate bodily therewith and having improved means for starting and stopping the hammering mechanism automatically in accordance with the predetermined positions assumed by the rotary dump. A further object is to provide improved fluid supply means for automatically connecting a fluid supply connection on the rotary dump with an extraneous source of pressure fluid. A still further object is to provide an improved releasable fluid supply coupling for connecting the fluid supply on the rotary dump to a source of pressure fluid extraneous to the dump. These and other objects and advantages of the invention will, however, hereinafter more fully appear.

20

45 In the accompanying drawings there is shown for purposes of illustration one form which the invention may assume in practice.

In these drawings:

Fig. 1 is a side elevational view, with parts in central longitudinal vertical section, of a rotary car dump with which an illustrative form of the invention is associated, showing a mine car in inverted dumping position on the dump.

Fig. 2 is a cross-sectional view taken substantially on line 2—2 of Fig. 1, showing the rotary dump in end elevation.

3

Fig. 3 is an enlarged detail sectional view taken substantially on line 3—3 of Fig. 2, showing the fluid supply coupling in connected position.

Fig. 4 is a sectional view taken on the plane of Fig. 3 showing the fluid supply coupling in disconnected position.

Fig. 5 is a view similar to Fig. 2, showing the rotary dump turned through 180° into its position wherein the mine car is right side up.

Fig. 6 is an enlarged vertical sectional view taken substantially on line 6—6 of Fig. 1, showing details of one of the hammering tools.

Fig. 7 is a detail view showing the inner pivoted coupling element of the fluid supply coupling.

Fig. 8 is a sectional view with parts in side elevation illustrating the solenoid actuated valve.

Fig. 9 is a diagrammatic view showing the automatic control means for the solenoid actuated valve.

In this illustrative embodiment of the invention, the improved hammering means generally designated 1 is associated with a rotary car dump generally designated 2. Evidently, the invention may be associated with other types of material unloading apparatus.

The rotary car dump is of a conventional design and includes a rotary car supporting structure or carrier 3 supported by circular end supports 4, 4 mounted on bottom rollers 5 carried by a suitable base 6. The rotary carrier or dump structure 3 includes longitudinal frame members 7 and 8 secured to transverse frame members 9 within the circular end supports 4 and cross supports 10 secured to the members 7 along the length thereof, thus providing a rigid rotary structure capable of supporting the weight of a loaded car such as a conventional mine car 11 of the type used in coal mines. Arranged longitudinally within the rotary carrier and secured to the cross supports 10 are track rails 12 which, when the rotary dump is in the position shown in Fig. 5, are aligned with the rails 13 and 14 (see Fig. 1) of a trackway leading to and from the rotary dump. The track rails 13, 14 may be laid on a suitable bed structure 15 laid on the floor or ground or, if desired, the track bed may be supported directly on the floor or ground with the lower portion of the rotary dump arranged in a suitable recess, such as a pit, in a well known manner. Secured to the inner sides of the transverse frame members 9 and intermediate frame members 16 secured to the longitudinal frame members 7 and 8, are side flanges or ledges 17 which are received in longitudinal guideways 18 on the sides of the mine car 11 when the latter is moved within the rotary dump, and these side flanges serve to support the mine car when the latter is in inverted position as shown in Figs. 1 and 2. The mine car has a body 19 which serves as a receptacle for receiving the loose coal or other material to be transported and the body is supported by wheels 20 adapted to travel along the track rails 13, 14 of the trackway leading to and from the rotary dump and along the track rails 12 within the rotary dump. Mounted on a platform 21 at one side of the rotary dump is a motor 22 for driving through a conventional clutch controlled transmission 23 a spur gear 24 which meshes with a large spur gear 25 on the outer periphery of one of the circular end supports 4 of the rotary dump. The transmission 23 embodies a conventional clutch mechanism operated by a hand lever 26 for connecting the gear 24 to the motor so that rotation of the dump may

4

be started and stopped under manual control as desired. Evidently, suitable automatic stop mechanism may be provided for interrupting the drive when the rotary dump has turned through 180° into its opposite positions as shown in Figs. 2 and 5.

Now referring to the means for imparting hammer blows to the car bottom when the mine car is in inverted position on the rotary dump, it will be noted that mounted on parallel supports 27, 27 secured to end plates 28, in turn secured to the cross supports 10 and the circular end supports 4, are hammering tools 29 which assume upright positions above the mine car as shown in Figs. 1 and 2 when the mine car is inverted. There are shown herein three hammering tools spaced longitudinally of the rotary dump as shown in Fig. 1 although a greater or smaller number of tools may be employed under certain conditions. Each of these hammering tools comprises, as shown in Fig. 6, a tubular guide cylinder 30 preferably welded to side plates 31 which are secured by screws 32 to the parallel supports 27. Attached as by tie rods 33 to the ends of the cylinders are end plates 34 and 35, the latter having a central bore 36. Slidably guided in each of the guide cylinders 30 is a conventional hammer motor 37 comprising a motor cylinder 38 containing a reciprocating hammer piston 39 for delivering impact blows to a tappet 40 guided in a front cylinder head 41. The forward portion of the front cylinder head 41 is received in a bore 42 in a front cylindric guide block 43 which slidably fits the bore of the guide cylinder 30, and also arranged in the bore of the front guide block is a bushing 44 which slidably receives and supports the shank 45 of a front striking bar 46. Arranged at the rear end of the motor cylinder is a rear cylindric guide block 47 also slidably received in the guide cylinder bore. The cylinder parts and the front and rear guide blocks are held in assembled relation as by tie bolts 48. The front striking bar 46 is received in the bore 42 of the front guide block and is held therein for limited reciprocatory movement by a pin and slot connection 49. The shank 45 of the striking bar projects rearwardly into the front cylinder head in position to receive the impact blows of the tappet 40 and the striking bar 46 projects forwardly through the bore 36 in the front head plate 35 of the guide cylinder in position to strike blows on the plane surface 50 of a channel iron 51 suitably rigidly secured to the bottom of the body 19 of the mine car 11. The hammer motor unit of each hammering tool is freely slidable within the bore of the guide cylinder 30 and each guide cylinder is slotted longitudinally at 52 along one side thereof. Fluid under pressure may be supplied to the hammer motors of the several hammering tools from a common supply pipe 53 extending longitudinally of and supported within the rotary dump, through flexible branch supply hoses 54 which pass through the guide cylinder slots 52 into connection with a conventional automatic fluid distributing means of the hammer motors. The fluid distributing means, as is well known to those skilled in the art, automatically distributes fluid through suitable ports and passages to the motor cylinder under the control of a conventional fluid distributing valve mechanism to effect rapid reciprocation of the hammer piston whenever the pressure fluid supply is turned on. Since the specific structure of the fluid distributing means does not per se enter into the present invention, further disclosure thereof herein

is unnecessary. The hammering tools above described are fully disclosed in the copending application referred to above.

The improved fluid supply means for the hammering tools comprises an automatic fluid supply coupling 56 having its outer element 57 pivotally mounted at 58 on an upright support 59 carried by the platform 21 at one side of the rotary dump. The outer coupling element 57 is vertically swingable about its pivot and a counter-balancing weight 60, arranged in a vertical tubular guide 61 carried on the platform, is connected by a cable 62 to the outer coupling element, and the cable is suitably guided on rolls carried by the upright support in the manner shown. This counterbalancing weight serves to maintain the coupling element 57 in the inclined position shown in Fig. 2 and when the coupling element is swung either upwardly or downwardly, it automatically returns to its initial position shown. The outer coupling element 57 comprises a tubular support 63 having fixed to its outer end a rear head 64 of a fluid cylinder 65 containing a reciprocable piston 66. The piston has a tubular piston rod 67 extending outwardly through a front cylinder head 68 and surrounding the piston rod within the cylinder is a coil spring 69 which constantly urges the piston toward its retracted position shown in Fig. 4. The cylinder 65 and the heads 64 and 68 are held in assembled relation as by tie bolts 70. Secured to the outer end of the piston rod is a hollow member 71 provided with a valve seat 72. Slidably mounted on the exterior cylindric surface of the member 71 is a valve carrying member 73 formed with a ported web 74 to which the stem 75 of an end seating valve 76 is secured and this valve is engageable with the valve seat 72. The member 73 has a rubber tip or nose 77 receivable, when the fluid supply coupling 56 is connected as shown in Fig. 3, in a conical socket 78 of an inner coupling element 79 on the rotary dump and the bottom of this socket is connected by a flexible supply hose 80 to the supply pipe 53. The inner coupling element has lateral trunnions 81 pivotally mounted in ears 82 integral with a bracket 83 secured to a support on the rotary dump. Oppositely acting coil springs 84 are connected to the ends of arms 85 secured to the trunnions 81 for holding the inner coupling element 79 in its central position shown in Fig. 7, and in the event the coupling element is tilted in one direction or the other, the springs automatically return the same to the central position shown. A flexible fluid supply hose 86 is connected to the upper end of the tubular support 63 of the outer coupling element 57 and leads to an automatic control valve 87 supported on the upright support 59, and this valve controls the connection of the hose 86 with a fluid supply pipe 88 leading to a source of pressure fluid supply or with an exhaust pipe 89, as hereinafter explained.

Now referring to the automatic control means therefor, it will be noted that arranged in a bore 90 in a valve casing 91 is a reciprocable spool valve 92 which is moved in one direction by a spring 93 and in the opposite direction by a solenoid 94. The fluid supply hose and the supply and exhaust pipes communicate with the valve-receiving bore 90 as shown in Fig. 8. Energization of the solenoid 94 is controlled by a conventional limit switch 95 (see Fig. 9) which is actuated by a cam 96 secured to a circular end support 4 of the rotary dump. When the dump is rotated to the position shown in Fig. 5, with the

mine car 11 turned right side up, the limit switch 95 is held open by the cam, breaking the circuit to the solenoid, deenergizing the latter and the spool valve 92 is moved by the spring 93 to its right-hand position as viewed in Fig. 8, with the supply pipe 88 cut off and the supply hose 86 vented to atmosphere through exhaust pipe 89. When the supply hose 86 is connected to exhaust, the fluid in the cylinder 65 is vented so that the coil spring 70 moves the piston 66 to its retracted position shown in Fig. 4 with the nose 77 of the outer coupling element 57 disconnected from the inner coupling element 79 on the rotary dump. When the nose 77 is released from the socket in the inner coupling element and pressure fluid is supplied through hose 86 and tubular support 63 to the cylinder 65 and through the tubular piston rod 69 to the hollow interior of the member 71, the pressure fluid acts on the valve 76 to hold the latter outwardly against its seat 72 as shown in Fig. 4. When the dump is rotated to turn the mine car 11 in its inverted position shown in Figs. 1 and 2, the cam 96 on the rotary dump actuates the limit switch 95 to close the circuit, thereby energizing the solenoid 94 to move the spool valve 92 to the left from its position shown in Fig. 8, with the exhaust 89 closed and the supply hose 86 connected to the supply pipe 88. Pressure fluid may then flow through hose 86 and the tubular support 63 to the cylinder 65, the pressure fluid acting on the piston 66 to move the latter forwardly to the position shown in Fig. 3, forcing the rubber nose 77 tightly into the conical socket 78 of the inner coupling element, thereby to connect the fluid supply coupling 56. As the rubber nose 77 is forced into the conical socket in the inner coupling element, the valve 76 is unseated, opening the fluid supply to the hammering tools.

The general mode of operation of the rotary dump is as follows. When the rotary dump is in the position shown in Fig. 5, a loaded mine car 11 may travel along the trackway 13 leading to the rotary dump and along the track rails 12 in the dump and as the mine car moves along the rails 12 onto the rotary dump, the side flanges 17 are received in the guideways on the mine car. The operator may then start the motor 22 and manipulate the lever 26 to effect rotation of the dump through the gearing 24, 25 from the position shown in Fig. 5 through 180° to the position shown in Figs. 1 and 2, wherein the mine car is inverted to discharge its contents, and the gearing 24, 25 may then be disconnected from the motor in any suitable manner either manually or automatically. As the rotary dump turns from the position shown in Fig. 5 to the position shown in Fig. 2, the hammering motors 37 of the hammering tools 29 slide inwardly along their guides 30 from their inverted inactive position to their operative position shown in Fig. 6, with the striking bar 46 in engagement with the surface 50 at the bottom of the mine car and as the rotary dump approaches the position shown in Fig. 2, the cam 96 on the dump actuates the limit switch 95 to energize the solenoid 94 to open the slide valve 92, thereby to supply pressure fluid from the supply pipe 88 past the valve and through the supply hose 86 and tubular support 63 to the cylinder 65, thereby moving the piston 66 forwardly to effect connection of the fluid supply coupling 56. When the fluid supply coupling is connected, pressure fluid may flow through the supply hose 80, supply pipe 53 and branch hoses 54 to the hammering motors 37 to effect hammering on the car bottom, thereby

to release the wet and sticky coal or other material which may be packed in the car bottom. When the inverted mine car is completely unloaded, the operator may manipulate the lever 26 to effect rotation of the dump from the position shown in Fig. 2 through 180° back to its position shown in Fig. 5 to turn the empty car right side up, and upon initiation of rotation of the dump toward the position shown in Fig. 5, the cam 96 causes the limit switch to open, breaking the circuit to the solenoid to deenergize the latter. When the solenoid is deenergized, the spool valve 92 is moved to the right, as viewed in Fig. 8, by the coil spring 93, cutting off the fluid supply and connecting the supply hose 86 with the exhaust pipe 89, thereby venting the cylinder 65 and effecting automatic release of the fluid supply coupling 56. Upon initiation of rotation of the rotary dump from the position shown in Fig. 2, the inner coupling element on the dump moves slightly away from the coupling element prior to the disconnection of the coupling and as a result, the outer coupling element 57 swings about its pivot 58 while, at the same time, the inner coupling element 58 rocks on its pivot until the coupling is disconnected by venting of the pressure fluid. As previously stated, the inner coupling element and the outer coupling element automatically return to their initial positions shown when disconnected. When the rotary dump is in the position shown in Fig. 5, with the empty mine car turned right side up, the mine car may then be moved along the track rails 12 from the rotary dump onto the trackway 14 leading from the dump.

As a result of this invention, it will be noted that a rotary car dump is provided having associated therewith improved means for hammering on the bottom of an inverted mine car on the dump to release any wet and sticky material which might be solidly packed in the car bottom. It will further be evident that by the provision of the improved automatic control means, the hammering tools on the rotary dump are automatically rendered effective to hammer on the car bottom when the dump is rotated to invert the mine car, and are automatically rendered inactive upon rotation of the dump toward its position wherein the mine car is turned right side up. It will further be evident that by the provision of the improved automatic fluid supply coupling, pressure fluid is automatically supplied to the hammering tools when the dump is rotated to invert the mine car and the fluid supply to the hammering tools is automatically discontinued upon initiation of rotation of the rotary dump toward its position wherein the car is turned right side up. Other uses and advantages of the invention will be clearly apparent to those skilled in the art.

While there is in this application specifically described one form which the invention may assume in practice, it will be understood that this form of the same is shown for purposes of illustration, and that the invention may be modified and embodied in various other forms without departing from its spirit or the scope of the appended claims.

What I claim as new and desire to secure by Letters Patent is:

1. In a material unloading apparatus, the combination comprising a rotary car dump adapted to receive a loaded car and to invert the car to discharge its contents, fluid actuated hammering means on said rotary dump for hammering on

the bottom of the inverted car, and means for supplying fluid from an extraneous source to said hammering means comprising a coupling element on said rotary dump, a coupling element extraneous to said dump, and fluid actuated means for moving said last mentioned coupling element into fluid tight engagement with said first mentioned coupling element.

2. In a material unloading apparatus, the combination comprising a rotary car dump adapted to receive a loaded car and to invert the car to discharge its contents, fluid actuated hammering means on said rotary dump for hammering on the bottom of the inverted car, and means for supplying fluid from an extraneous source to said hammering means comprising a coupling element on said rotary dump, a coupling element extraneous to said dump, fluid actuated means for moving said last mentioned coupling element into fluid tight engagement with said first mentioned coupling element, and means for pivotally mounting said first mentioned coupling element on said dump so that said second mentioned coupling element may move into engagement therewith even when said coupling elements are out of exact alinement.

3. In a material unloading apparatus, the combination comprising a rotary car dump for receiving a loaded mine car and rotatable to invert the car to discharge its contents, power operating hammering means mounted on said rotary dump for imparting hammer blows to the car when the latter is inverted, and means automatically controlled by rotation of said dump for supplying power medium to said hammering means when said dump assumes its position wherein the car is inverted, said supply means including a power medium conducting connection on said rotary dump and operatively connected to said hammering means, a power medium conducting connection extraneous to said dump and operatively connected to an extraneous source of power medium supply and means for bringing said connections into operative power medium conducting relation when said connections are in substantial registry.

4. In a material unloading apparatus, the combination comprising a rotary car dump for receiving a loaded mine car and rotatable to invert the car to discharge its contents, power operating hammering means mounted on said rotary dump for imparting hammer blows to the car when the latter is inverted, and means automatically controlled by rotation of said dump for supplying power medium to said hammering means when said dump assumes its position wherein the car is inverted, said supply means including a power medium conducting connection on said rotary dump and operatively connected to said hammering means, a power medium conducting connection extraneous to said dump and operatively connected to an extraneous source of power medium supply and means for bringing said connections into operative power medium conducting relation when said connections are in substantial registry, said last mentioned means including a power operated feeding device for said extraneous power medium conducting connection, control means for said feeding device and a control device for said control means including a control element rotatable with said rotary dump.

5. In a material unloading apparatus, the combination comprising a rotary car dump for receiving a loaded car and for inverting the car

to discharge its contents, power operated hammering means mounted on said rotary dump for imparting hammer blows to the car when the latter is inverted, and means for automatically supplying power medium to said hammering means when said rotary dump assumes its position wherein the car is inverted, said automatic supply means for the power medium including a releasable power medium conducting coupling and means for automatically connecting said coupling when said rotary dump assumes said position wherein the car is inverted.

6. In a material unloading apparatus, the combination comprising a rotary car dump for receiving a loaded car and rotatable to invert the car to discharge its contents, fluid operated hammering means mounted on said rotary dump for imparting hammer blows to the car when the latter is inverted, and means automatically controlled by rotation of said dump for supplying operating fluid to said hammering means when said dump assumes its position wherein the car is inverted, said supply means including a fluid conducting connection on said rotary dump and operatively connected to said hammering means, a fluid conducting connection extraneous to said dump and operatively connected to an extraneous source of fluid supply, and means for bringing said connections into operative fluid conducting relation when said connections are in substantial registry.

7. In a material unloading apparatus, the combination comprising a rotary car dump for receiving a loaded car and rotatable to invert the car to discharge its contents, fluid operated hammering means mounted on said rotary dump for imparting hammer blows to the car when the latter is inverted, and means automatically controlled by rotation of said dump for supplying operating fluid to said hammering means when said dump assumes its position wherein the car is inverted, said supply means including a fluid conducting connection on said rotary dump and operatively connected to said hammering means, a fluid conducting connection extraneous to said dump and operatively connected to an extraneous source of fluid supply, and means for bringing said connections into operative fluid conducting relation when said connections are in substantial registry, said last mentioned means including fluid operated feeding means for said extraneous fluid conducting connection, control valve means for said feeding means and a control device for said valve means including a control element rotatable with said rotary dump.

8. In a material unloading apparatus, the combination comprising rotary supporting means adapted to support a receptacle containing material to be unloaded and rotatable to invert the receptacle to discharge its contents, power operated means on said rotary supporting means and controlled by rotation of the latter for striking hammer blows on said receptacle whenever said supporting means is rotated to invert the receptacle, and means for supplying power medium to said power operated means including a power medium conducting element on said rotatable supporting means, a power medium conducting element extraneous to said supporting means and connectible to said first element to conduct power medium thereto, said first mentioned element being operatively connected to said power operated means and said extraneous element being operatively connected to an extraneous source of power medium supply, means

for effecting connection of said elements and control means including a control element rotatable with said supporting means for controlling said connection-effecting means.

5. In a material unloading apparatus, the combination comprising a rotary car dump for receiving a loaded mine car and rotatable to invert the car to discharge its contents, a fluid actuated hammering mechanism mounted on said rotary dump for imparting hammer blows to the car when the latter is inverted, a fluid supply for said hammering mechanism comprising a fluid supply coupling, said coupling including a coupling element on said rotary dump and having a conical socket, a coupling element extraneous to said dump and mounted for movement toward and from said socketed element and having a nose receivable in fluid tight engagement with the walls of said conical socket, a fluid actuated piston for moving said nose into engagement with the socket walls, and control means including a control element actuated by said rotary dump for effecting fluid supply to cause the fluid to act on said piston to actuate the latter when said coupling elements are brought into substantial registry.

10. In a material unloading apparatus, the combination comprising a rotary car dump for receiving a loaded mine car and rotatable to invert the car to discharge its contents, fluid actuated hammering mechanism on said rotary dump for imparting hammer blows to the car when the latter is inverted, and means automatically controlled by rotation of said dump for supplying pressure fluid to said hammering mechanism when said dump assumes its position wherein the car is inverted, said supply means including a fluid supply coupling, said coupling including a socketed coupling element on said rotary dump and pivotally mounted for rocking movement, a pivotally mounted coupling element extraneous to said dump and having a nose receivable in the socket of said first mentioned coupling element in fluid tight engagement with the socket walls 25 when said coupling elements are brought into substantial registry, and fluid actuated means for moving the nose of said second mentioned coupling element into said socket, said pivotal mountings for said coupling elements permitting fluid tight engagement of said nose with the socket walls even when said coupling elements are out of exact alignment.

11. In a material unloading apparatus, the combination comprising rotary supporting means 55 adapted to support a receptacle containing material to be unloaded and rotatable to invert the receptacle to discharge its contents, a power operated hammer mechanism on said rotary supporting means and controlled by rotation of the latter for striking hammer blows on said receptacle whenever said supporting means is rotated to invert the receptacle, and means for supplying power medium to said power operated hammer mechanism comprising a power medium conducting coupling including a coupling element on said rotary supporting means and having a conical socket, a power medium conducting coupling element mounted extraneous to said supporting means for movement toward and from said socketed element when said elements are brought into substantial registry and having a nose receivable in tight sealing contact with the walls of said conical socket, a power operated feeding element for moving said nose into contact with the socket walls, means for retracting said feeding element

when power medium supply to said feeding element is discontinued, and control means including a control element rotatable with said supporting means for controlling the supply of power medium to said feeding element for effecting such connection of said coupling elements when said receptacle assumes its inverted position and for interrupting such supply to said feeding element when said receptacle is moved toward its upright position.

12. In a material unloading apparatus, the combination comprising rotary supporting means adapted to support a receptacle containing material to be unloaded and rotatable to invert the receptacle to discharge its contents, a power operated hammer mechanism on said rotary supporting means and controlled by rotation of the latter for striking hammer blows on said receptacle whenever said supporting means is rotated to invert the receptacle, and means for supplying power medium to said mechanism comprising a power medium conducting coupling including a coupling element on said rotary supporting means and having a socket and a power medium conduit leading therefrom, a coupling element extraneous to said supporting means and having a power medium conduit therethrough and a control element associated therewith for controlling power medium flow, power operated means for moving said second mentioned coupling element into tight sealing contact with the socket walls of said first mentioned coupling element when said coupling elements are brought into substantial registry upon rotation of said supporting means to invert the receptacle, means associated with said second mentioned coupling element for moving said control element into its open position when said coupling elements are brought into contact to permit power medium flow through said coupling elements to said first mentioned power medium conduit, and means for automatically retracting said second mentioned coupling element when power medium flow to said moving means is discontinued.

13. In a material unloading apparatus, the combination comprising a rotary car dump for receiving a loaded mine car and rotatable to invert the car to discharge its contents, a fluid operated impact mechanism on said rotary dump for imparting impact blows to the car when the latter is inverted, and means for supplying operating fluid to said impact mechanism comprising a fluid conducting coupling, said coupling including a fluid cylinder extraneous to said rotary dump and containing a reciprocable hollow piston having its tubular piston rod extending outwardly from said cylinder, means for supplying fluid to said cylinder to urge said piston forwardly, means for retracting said piston when said cylinder is vented, a fluid conducting coupling element carried at the outer end of said piston rod, a fluid conducting coupling element on said rotary dump and with which said reciprocable coupling element is movable into coacting engagement when said coupling elements are brought into substantial registry, the fluid in said cylinder flowing through

said piston rod and through said coacting coupling elements to said impact mechanism, and control means including a control element rotatable with said rotary dump for controlling fluid flow to said fluid supply means for said cylinder and for venting said cylinder.

14. In a material unloading apparatus, the combination comprising a rotary car dump for receiving a loaded mine car and rotatable to invert the car to discharge its contents, a fluid operated impact mechanism mounted on said rotary dump for imparting impact blows to the car when the latter is inverted, and means for supplying operating fluid to said impact mechanism comprising a fluid conducting coupling, said coupling including a fluid cylinder extraneous to said rotary dump and containing a reciprocable hollow piston having its tubular piston rod extending outwardly from said cylinder, means for supplying fluid to said cylinder to urge said piston forwardly, means for retracting said piston when said cylinder is vented, a fluid conducting coupling element carried at the outer end of said piston rod, a fluid conducting coupling element on said rotary dump and with which said reciprocable coupling element is movable into coacting engagement when said coupling elements are brought into substantial registry, the fluid in said cylinder flowing through said piston rod and through said coacting coupling elements to said impact mechanism, a valve device carried by said reciprocable coupling element and movable relative to said piston rod when said coupling elements are moved together for controlling fluid flow through said coupling elements, and control means including a control element rotatable with said dump for controlling the fluid supply to said fluid supplying means of said cylinder and for venting said cylinder.
